POCKETED MOVING SURFACE GAME

Filed May 26, 1926

FIG. 1

FIG. 2

FIG. 3

INVENTOR.
JOSEPH W. BRENKERT
BY *A. B. Bowman*
ATTORNEY

UNITED STATES PATENT OFFICE.

JOSEPH W. BRENKERT, OF SAN DIEGO, CALIFORNIA.

POCKETED MOVING-SURFACE GAME.

Application filed May 26, 1926. Serial No. 111,735.

My invention relates to games, particularly to parlor or school games.

The objects of my invention are: first, to provide an interesting and educational game which may be played by two or more persons and which may be equally enjoyed by children and adults; second, to provide an educational game whereby the learning of addition, multiplication and subtraction is encouraged and facilitated; third, to provide a game of this class in which interest is stimulated by embodying the cunning and trickery of a fox in the movements of the game members or pieces in rolling or otherwise moving of the same from a retaining portion or depression into certain pockets or openings and in avoiding the movements of the same into other pockets or traps; fourth, to provide a game of this class in which the counting or points is made by moving the movable game members or pieces on the game board member and dropping the same into pockets or a channel representative of the underground lair of foxes; fifth, to provide an educational game of this class whereby children not far advanced in arithmetic may play the game by adding points only, and whereby others more advanced may use addition and multiplication in figuring the points to their credit, and further, whereby those still farther advanced may use addition, multiplication and subtraction; sixth, to provide a game of this class whereby one or more balls or other game members may be used at the same time in playing the game; seventh, to provide a game of this class which may be played by any number of persons, as desired; eighth, to provide a novel container for a game of this class which serves as one of the members of the game device when playing the same and which also serves to enclose the same and game pieces; ninth, to provide a container for a game of this class in which a hollow game board member is rotatably mounted and in which loose game members or pieces are permitted to drop from the upper side of the game board member and retained therein until the game board member is rotated relative to the container, forming an opening for removing the movable game pieces, and tenth, to provide as a whole a novelly constructed and arranged game apparatus of this class and one which is very simple and economical of construc-

tion, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a top view of my game apparatus or device in its preferred form of construction, showing the cover thereof removed; Fig. 2 is a sectional elevational view thereof, taken through 2—2 of Fig. 1, and Fig. 3 is a side elevational view thereof, taken at 3—3 of Fig. 1, showing a portion thereof broken away and in section to facilitate the illustration and showing a fragmentary portion of the cover positioned thereover.

Like characters of reference refer to similar parts and portions throughout the several views of the drawings.

The game or game apparatus is in a container or casing 1 consisting of a circular bottom 1^a and a flange 1^b extending upwardly from the periphery thereof. Within the container or casing 1 is loosely positioned the member 2, which for convenience will be hereafter called the game board or game board member. Said game board member is substantially flat at its upper side, as indicated by 2^a, and provided at its periphery with a downwardly extending flange 2^b, which supports the upper or flat portion 2^a of the game board member from the bottom 1^a of the casing 1. At the central portion of the upper portion 2^a of the member 2 is provided a shallow spherical depression 2^c for receiving and retaining a plurality of game pieces 3, 4 and 5 in the form of balls, which are variously colored, those shown in Fig. 1 being colored, respectively, white, red and black. Positioned around the central depression 2^c and arranged in a circle therearound is a plurality of pockets or openings 2^d, which communicate with the space at the under side of the top portion of the game board member 2. These pockets or openings 2^d are slightly larger than the balls 3, 4 and 5 and permit said balls to pass into the channel or pas-

sage at the under side of the member 2, which, for convenience, will be termed the "lair". In front of, or between the depression 2^c and openings 2^d are provided slightly raised portions 2^f, which extend circularly around the forward portions of openings 2^d and simulate the dirt mounds at the entrance openings to the lair of the foxes. Positioned between the circularly arranged openings 2^d and the edge of the upper or flat portion of the game member 2 are other openings 2^e, which are also circularly arranged around the holes or openings 2^d, but are positioned in staggered relation relative to the same. These openings 2^e are smaller than the balls 3, 4 and 5 and will not permit the same to drop therethrough, but provide pockets for catching or retaining the balls when the same are rolled over the upper surface of the portion 2^a of the member 2. These openings 2^e are arranged in the field and represent bogus passage holes or traps arranged by the hunter to catch the fox.

25 The game is played by placing one, two or three balls in the depression 2^c, which represents the sunny den of the foxes. The casing 1 is then tilted so that one or all of the balls leave the depression and is or are rolled over the flat upper surface of the portion 2^a of the game board member until the same drop into the openings 2^d into the lair or into the traps 2^e. It will be here noted that when a ball passes between two raised portions or mounds 2^f, the same might drop either into the openings 2^d or into one of the traps, the trick of the game being to drop the balls into the openings 2^d at one time and into the openings or traps 2^e at other times.

40 In the downwardly extending flange 2^b of the game board member 2 is provided an opening 2^g, which is adapted, when the game board member is shifted to a certain position, to register with a correspondingly shaped opening 1^e in the upwardly extending flange of the casing 1, as shown in Fig. 3. When said openings 2^g and 1^e are in registry, the balls dropped into the space between the game board member and the bottom of the casing are permitted to be removed. When said openings are not in registry, the space below the member 2 forms a convenient receptacle for the balls from which the same cannot be readily lost. The 55 openings in the members 1 and 2 are closed when normally playing the game. Over the open end of the casing 1 is provided a cover 6, which, with the casing 1, provides a convenient and inexpensive casing or enclosure for the game. Said casing 1, the game board member 2 and the cover 6 are preferably made of a light gage sheet metal or of cardboard, or other suitable material. It will be here also noted that the members 1 and 2 60 may be integrally made if desired.

The game when played by children when learning or practicing addition is played with one ball at a time. This ball is placed in the depression or den and the device tilted until the ball falls either in one of the openings 2^d or into one of the traps 2^e. When the ball falls into one of the openings 2^d, the number 2^h near or associated with the particular opening through which the ball drops is credited to the player. If the ball drops into one of the openings 2^e, the player receives nothing. This process is repeated with the other balls and the aggregate sum of the points credited to the player.

If addition and multiplication are to be practiced and more complication and higher scores involved, the white ball is used for addition and the red one for multiplication. These balls may be used either singly or simultaneously. If the white ball falls in the opening marked "6" and the other falls in the opening marked "3", the score of the player would be 6 plus 3 times 3, or 15. If the red ball falls into one of the traps and the white one into the hole marked "6", the score would be 6 plus 0.

When all three balls are used, either singly or simultaneously, the white ball would be used for a positive point or for addition, the red one for multiplication or the square of the number at the hole through which the ball drops, and the black ball will register a negative point. Thus, when the white ball falls into the opening marked "6", the red one into the opening marked "3" and the black one into the opening marked "9", the result would be 6 plus three times 3 minus 9, or 6.

Though I have shown and described a particular construction, combination and arrangement of parts and portions of my game apparatus, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a game, a game board and game members, said board having a depression at its middle portion, and a plurality of openings in said board around said depression, each opening being adapted to receive a plurality of said game members and discharge the same below the upper surface of the game board member.

2. In a game, a game board and game members, said board having a depression at its middle portion, a plurality of openings in said board around said depression adapted to receive the whole of said game members, and other openings in said game board positioned outwardly from said first mentioned

openings adapted to temporarily check the movements of said game members.

3. In a game, a game board and game members, said board having a depression at its middle portion, a plurality of openings in said board around said depression adapted to receive the whole of said game members, and pockets arranged in said board between said openings and the outer portions thereof adapted to temporarily check the movements of said game members.

4. In a game, a game board and game members, said board having a depression at its middle portion, a plurality of openings in said board surrounding said depression adapted to receive said game members, and raised portions in said board between said openings and said depression.

5. In a game apparatus, a game board member and game members, said game board member having a game member retaining portion, a plurality of pockets arranged around said game member retaining portion adapted to receive said game members, and a plurality of other smaller pockets arranged contiguous to said other pockets for receiving and holding said game members.

6. In a game apparatus, a game board member and game members, said game board member having a game member retaining portion, a plurality of pockets arranged around said game member retaining portion adapted to temporarily receive and hold said game members and to permit said game members again to be discharged therefrom to the upper surface of the game board member by slight agitation of the latter, and raised portions positioned between said pockets and said game member retaining portion.

7. In a game apparatus, a game board member and game members, said game board member having a game member retaining portion, pockets arranged around said game member retaining portion adapted to temporarily receive and hold said game members and to permit said game members again to be discharged therefrom to the upper surface of the game board member by slight agitation of the latter, raised portions positioned between said pockets and said game member retaining portion and spaced from each other, and other pockets in said game board member positioned substantially in line with the space between said raised portions and said game member retaining portion adapted to receive the whole of each of said game members.

8. In a game apparatus, a game board member, and a plurality of balls, said game board member having a ball retaining portion, a plurality of raised portions arranged around said ball retaining portion and spaced from each other, and pockets in said game board member positioned substantially

in line with the spaces between said raised portions and said ball retaining portion, said pockets being adapted to receive and hold said balls.

9. A game device, having a game member retaining portion at its upper side and openings around said portion connecting the upper side with a game member channel below said upper side, and raised portions on said device in association with said openings and positioned between the same and said game member retaining portion, said raised portions being spaced from each other, said device having game member receiving pockets in its upper side and arranged exteriorly relative to said openings.

10. A game case, having spaced apart upper and lower walls forming a game member receptacle between said walls, said upper wall having a large game member retaining depression and game member receiving openings spaced from and arranged around said game member retaining depression, said openings connecting the upper side of said upper wall with the game member receptacle between said walls.

11. A game case, having spaced apart upper and lower walls forming a receptacle between said walls, said upper wall having a game member retaining portion and game member receiving openings spaced from and arranged around said game member retaining portion, said openings connecting the upper side of said upper wall with the space between said walls, said openings being differently numbered and having raised portions adjacent one side of the same and spaced from each other, said raised portions being positioned between said openings and said game member retaining portion.

12. A game case, having spaced apart upper and lower walls forming a receptacle between said walls, said upper wall having a game member retaining portion and game member receiving openings spaced from and arranged around said game member retaining portion, said openings connecting the upper side of said upper wall with the space between said walls, said openings being differently numbered and having raised portions adjacent one side of the same and spaced from each other, said raised portions being positioned between said openings and said game member retaining portion, said upper wall having small game member receiving pockets arranged exteriorly of said openings and substantially in line with the space between said raised portions and said game member retaining portion.

13. In a game apparatus, a circular casing having a bottom and upwardly extending side flanges, and a game board member loosely positioned therein, said game board member having a substantially flat upper side with a downwardly extending flange at

its periphery, said flange supporting said substantially flat portion from the bottom of said casing forming a game member receiving space, said substantially flat portion having openings therein for admitting game members from the upper side thereof to the game member receiving space between said casing and said game board member.

14. In a game apparatus, a circular casing having a bottom and upwardly extending side flanges, and a game board member loosely positioned therein, said game board member having a substantially flat upper side with a downwardly extending flange at its periphery, said flange supporting said substantially flat portion from the bottom of said casing forming a game member receiving space, said substantially flat portion having openings therein for admitting game members from the upper side thereof to the game member receiving space between said casing and said game board member, said game board member being rotatable within said casing, the flanges of said casing and said game board member having openings adapted to align with each other when mutually rotating said casing and said game board member for discharging game members from said game member receiving space.

15. In a game apparatus, a circular casing

having a bottom and upwardly extending side flanges, a game board member loosely positioned therein, said game board member having a substantially flat upper side with a downwardly extending flange at its periphery, said flange supporting said substantially flat portion from the bottom of said casing forming a game member receiving space, said substantially flat portion having openings therein for admitting game members from the upper side thereof to the game member receiving space between said casing and said game board member, said game board member being rotatable within said casing, the flanges of said casing and said game board member having openings adapted to align with each other when mutually rotating said casing and said game board member for discharging game members from said game member receiving space, and a cover having a downwardly extending flange at its periphery adapted to be positioned over the outer side of the flange of said casing for enclosing the same and for covering the opening in the flange thereof.

In testimony whereof, I have hereunto set my hand at San Diego, California, this 15th day of May, 1926.

JOSEPH W. BRENKERT.
